CLAIM

The ornamental design for a handset, as shown and described.

DESCRIPTION

FIG. 1 is a bottom view of a handset showing my new design;

FIG. 2 is a right side view thereof;

FIG. 3 is a front view thereof;

FIG. 4 is a left side view thereof;

FIG. 5 is a top view thereof;

FIG. 6 is a rear view thereof; and,

FIG. 7 is a front perspective view thereof.

The broken lines that delineate the two unshaded rectangular regions on the rear of the handset (shown in FIG. 6) represent boundaries of the claimed design and form no part of the claimed design. The unshaded regions defined by these broken lines form no part of the claimed design.
